UNITED STATES PATENT OFFICE.

MARTIN CHRISTENSEN, OF RACINE, WISCONSIN, ASSIGNOR TO CHRISTENSEN MACHINE CO., OF RACINE, WISCONSIN, A CORPORATION OF WISCONSIN.

PUSHER MEMBER FOR BOOK-STITCHING MACHINES.

1,360,886.

Specification of Letters Patent. Patented Nov. 30, 1920.

Application filed December 20, 1919. Serial No. 346,250.

To all whom it may concern:

Be it known that I, MARTIN CHRISTENSEN, a citizen of the United States, and resident of Racine, in the county of Racine and 5 State of Wisconsin, have invented new and useful Improvements in Pusher Members for Book-Stitching Machines, of which the following is a description, reference being had to the accompanying drawings, which 10 are a part of this specification.

The present invention relates to certain new and useful improvements in conveyers for book stitching machines and refers more particularly to the pusher members 15 carried by the conveyers.

The primary object of the present invention is to provide a pusher member for a book stitching machine conveyer especially adapted for use with books having the ends 20 of the cover extended beyond the ends of the book leaves and has for one object to provide what may be called an adjustable stop for leaves and extension covers.

Another object of my invention is to provide a conveyer pusher member having 25 means for feeding the cover and leaves of a book to a stitcher in their proper relative positions which may be readily adjusted and which is readily detachable from the conveyer.

A further object of this invention is to provide a pusher member of the class described in which the book leaf engaging members serve to secure the pusher member 35 to the book stitching machine conveyer.

With the above and other objects in view which will appear as the description proceeds my invention resides in the novel construction, combination, and arrangement of 40 parts substantially as described and herein-after more particularly defined by the appended claims, it being understood that such changes in the precise embodiment of the herein disclosed invention may be made as 45 come within the scope of the claims.

In the accompanying drawings I have illustrated one complete example of the physical embodiment of my invention constructed according to the best mode I have 50 so far devised for the practical application of the principles thereof, and in which:

Figure 1 is a side view of a movable saddle conveyer illustrating my novel form of pusher member as secured thereto.

Fig. 2 is a view part in section and part

in elevation taken through the movable saddle conveyer on the line 2—2 of Fig. 1.

Fig. 3 is a perspective view of my novel form of pusher member detached from the conveyer, and

Fig. 4 is a detailed fragmentary sectional view taken on the line 4—4 of Fig. 2, said view illustrating the manner in which the book is positioned on the saddle with the cover extended beyond the leaves.

The particular form of saddle conveyer I employ with my novel form of pusher member is immaterial and in the drawing I have illustrated the same as a plurality of inverted V-shaped saddles 5 having depending lugs for pivotally receiving the conveyer chain links 6, each member 5 having apertures 7 in its side walls for removably receiving a pusher member 8.

The pusher member 8 consists of a U-shaped member 9 adapted to be positioned with its arms projecting from the sides of any one of the members 5 through the apertures 7 as depicted in Fig. 2 and said member is secured in this position by means of 80 book leaf engaging stops 10. A leaf engaging member 10 is secured to each arm of the U-shaped member 9 close to the point where it projects from the adjacent side wall of the saddle member 5 and is secured 85 to said member by means of a shank portion 11 which is engaged in an aperture 12 formed in said member.

The leaf engaging members 10 have their shanks secured in the apertures 12 by 90 means of suitable binding or set screws 13 which permit the ready adjustment of said members so that the relative distance between the front face of each book leaf engaging member and the front face of the 95 member 9 may be readily varied.

In use, the stop 9 is adjusted so that when the book leaves 14 are placed upon the conveyer they will engage against the stop 10 which is as thick or thicker than the 100 number of leaves being worked upon and when the book cover 15 is placed thereon the same will engage the member 9 which provides a book cover stop or engaging member. If it is desired to have 105 the ends of the cover 15 to project say a quarter of an inch beyond the ends of the leaves the stops 10 are so adjusted.

As will be readily seen by reference to Fig. 2 the stops 10 provide means for secur-

ing the members 9 to the conveyer saddle members 5 and that the pusher members may be secured to the conveyer in varying positions.

5. What I claim as my invention is:

1. A pusher member for a stitching machine conveyer, comprising a leaf engaging part, and a cover engaging part having its work engaging face offset with respect to 10 the work engaging face of said leaf engaging part, whereby the cover and leaf of a book to be stitched are positioned in their proper relative positions.

2. A pusher member for a stitching machine conveyer, comprising a leaf engaging part, a cover engaging part having its work engaging face offset with respect to the work engaging face of said leaf engaging part, whereby the cover and leaf of a 20 book to be stitched are positioned in their proper relative positions, and means for adjusting the distance between the work engaging faces of said parts.

3. A device of the class described, comprising a member for engaging a book cover, and a second member carried by said first mentioned member for engaging a book leaf, so that the ends of the cover will extend beyond the adjacent ends of the leaf.

30 4. A pusher member for a stitching machine conveyer comprising a book cover engaging member, and a book leaf engaging member adjustably carried by the cover engaging member and including a stop having a shank portion adjustably secured to the cover engaging member.

35 5. A pusher member for a stitching ma-

chine conveyer comprising a book cover engaging member, a book leaf engaging member, a securing shank formed on the leaf engaging member and slidably mounted in an aperture in the cover engaging member, and means releasably securing the shank in said aperture so that the distance between the front faces of the cover engaging member 45 and the leaf engaging faces may be adjusted.

6. The combination with a stitching machine conveyer including inverted V-shaped saddle members, of means for positioning a book cover and leaves on the saddle members of the conveyer comprising a U-shaped member passed through the sides of one of the saddle members and having its ends extended therefrom, and a book leaf engaging 55 stop secured to each arm of said U-shaped member close to the adjacent side of the saddle member.

7. The combination with a stitching machine conveyer including inverted V-shaped 60 saddle members, of means for positioning a book cover and leaves on the saddle members of the conveyer comprising a U-shaped member passed through the sides of one of the saddle members and having its 65 ends extended therefrom, a book leaf engaging stop secured to each arm of the U-shaped member close to the adjacent side of the saddle member, and means for adjustably varying the relative distance between the leading faces of the U-shaped member and the book leaf stops.

In testimony whereof, I affix my signature.

MARTIN CHRISTENSEN.
